CLAIM

The ornamental design for a mirror and glass combination shower enclosure, as shown and described.

DESCRIPTION

FIG. 1 is a front elevational view of the new mirror and glass combination shower enclosure design;

FIG. 2 is a rear elevational view thereof;

FIG. 3 is a left side elevational view thereof, the right side view is a mirror image of the left side; and,

FIG. 4 is a top view thereof.

The shaded lines that define the mirror and glass panels included in the claimed design form no part thereof.
